UNITED STATES PATENT OFFICE

HARRY CHARLES NORLEY, OF NORTH BAY, ONTARIO, CANADA, ASSIGNOR TO CANADIAN ATLAS STEELS LIMITED, OF WELLAND, ONTARIO, CANADA, A CORPORATION OF CANADA

DRILL

Application filed November 13, 1931. Serial No. 574,830.

My invention relates to improvements in drills, and the object of the invention is to devise a connection between the steel shank and bit particularly adaptable for use when the drill shank is operating horizontally such as in rock mining, quarrying and tunneling and which will simplify and cheapen the manufacture by avoiding threading and other expensive operations, and it consists essentially of the arrangement and construction of parts as hereinafter more particularly explained.

Fig. 1 is a perspective view of a portion of a drill shank and bit and showing my connector applied thereto.

Fig. 2 is a plan sectional view taken on line 2—2 Fig. 3.

Fig. 3 is a sectional view on line 3—3 Fig. 2.

Fig. 4 is a sectional view on line 4—4 Fig. 2.

Figs. 5, 6 and 7 are perspective details of the shank, connector and bit separated apart.

In the drawing like letters of reference indicate corresponding parts in each figure.

1 indicates the lower portion of a shank which may be octagonal in section as shown or cylindrical or any other form desired. The lower end of the shank is provided with 20 a cylindrical tapered portion 2. 3 is a bit provided with a recess 3^x in its upper face in which the lower end of the shank portion 2 of the drill shank fits.

Between the cutting portions 3° of the bit 35 and wall of the recess 3^x is cut away to form notches 4 which are preferably placed diametrically opposite and from which extend in opposite directions internal cam grooves 4^x and 4°, the groove inclining 40 downward slightly as indicated by dotted lines in Fig. 4 and into which diametrically opposite projections 5 and 5^x extend when the parts are connected together. When making such connection the tapered portion

45 2 of the shank is fitted into the recess 3^x, the projections 5 and 5^x passing into the notches 4. When in this position the shank and bit are rotated relatively in opposite directions so that the projections 5 and 5^x pass into the 50 internal cam grooves 4^x and 4° engaging the

downwardly inclined upper wall thereof so as to draw or cam up the bit so that the portion 2 of the steel bit fits tight in the recess 3^x leaving a clearance when the shank first enters the bit $\frac{1}{16}$ of an inch which is taken up by the impact.

In operation the bit rotates in a counter clockwise direction and, therefore, as such operation takes place there is a tendency for the bit to increase in tightness as the drive 60 is carried from the shank to the projections 5 and 5^x thereof to the walls of the recesses 4^x and 4° of the bit. In order to lock the parts in the above position I provide a split spring ring 6 which surrounds the portion 2 65 of the steel shank and is provided with downward projections 6^x and 6° which fit into the notches 4 and thereby close the open ends of the slots 4^x and 4° so that when the rotation of the bit is reversed prior to withdrawal the 70 parts will not disengage. When the bit is withdrawn all it is necessary to do is to draw the spring ring 6 upward upon the portion 2 of the shank so as to carry the projections 6^x and 6° out of the notches 4 permitting the 75 projections 5 and 5^x passing from the grooves 4^x and 4° into such notches so that the bit may be withdrawn longitudinally from the end of the shank.

From this description it will be seen that 80 I have devised a very simple device for connecting a drill bit to a shank which is particularly adaptable for use when the bit and shank are revolving horizontally, which will enable the bit being easily removed from the 85 shank when withdrawn from the bore to be replaced or renewed whenever desired and which will eliminate the threading of the bit upon the shank and locking the bit on the thread, which has been found in practice to 90 be not only expensive and costly to manufacture but also not altogether practical in operation.

What I claim as my invention is:

1. The combination with a drill shank having a cylindrical end, of a drill bit provided with a recess into which the end of the drill shank fits, means for engaging the bit and shank together by rotary movement, and a split spring ring mounted upon the shank, 100

and means carried by the ring for preventing disengagement of the bit.

2. The combination with a drill shank having a cylindrical end, of a bit having a recess into which the shank end fits and having a notched wall, means engaging the bit and the shank together operated by the relative rotation thereof, and a split spring ring mounted upon the cylindrical portion of the shank and engaging the notched portion of the bit to prevent disengagement of the parts.
3. The combination with a drill shank having a cylindrical end, of a bit having a recess into which the shank end fits, said recess having a notched wall and a circumferential internal groove extending from said notch portion, a projection extending from the cylindrical portion of the shank adapted to fit into the notch portion of the bit, and to pass by circumferential movement between the bit and shank into the internal groove thereof, a spring split ring mounted upon the cylindrical portion of the shank and provided with a projection fitting the notch of the bit.
4. The combination with a drill shank, of a bit having a recess into which the shank end turnably fits, a projection and coacting bayonet slot connection between the shank and bit, and a withdrawable stop in the slot for preventing disengagement of said projection and slot.

HARRY CHARLES NORLEY.
